COMBINED EYEGLASS TEMPLE AND HEARING AID CASING

Clayton D. Mullin, St. Paul, John F. Rose, Minneapolis,
and Harold W. Darr, Edina, Minn., assignors to Maico
Electronics, Inc., Minneapolis, Minn., a corporation of
Minnesota

Application September 22, 1958, Serial No. 52,705

Term of patent 14 years

(Cl. D57—1)

Fig. 1 is a top plan view of a combined eyeglass temple and hearing aid casing, showing our new design;

Fig. 2 is a front elevation view;

Fig. 3 is a bottom plan view thereof; and

Fig. 4 is a rear elevation view.

We claim:

The ornamental design for a combined eyeglass temple and hearing aid casing, as shown.
